ATTORNEYS:

UNITED STATES PATENT OFFICE.

THEODORE W. FOSTER, OF PROVIDENCE, RHODE ISLAND.

DESIGN FOR A BACK FOR TOILET-BOXES, MIRRORS; OR SIMILAR ARTICLES.

SPECIFICATION forming part of Design No. 36,011, dated August 19, 1902.

Application filed June 30, 1902. Serial No. 113,882. Term of patent 7 years.

To all whom it may concern:

Be it known that I, THEODORE W. FOSTER, a citizen of the United States, residing at Providence, in the county of Providence and State of Rhode Island, have invented and produced a new, original, and ornamental Design for the Back of a Toilet-Box, Mirror, or Similar Article, of which the following is a specification, reference being had to the accompanying drawings, forming part thereof.

Figure 1 is a plan view, and Fig. 2 a transverse sectional view, of the back, showing my design.

As shown in the drawings, the shape of the back is circular, and my design consists of the raised representation of a male and female figure sitting in a swing surrounded with foliage and tropical grasses, inclosed with raised

marginal representations of scrolled and twisted tropical plants, vines, and scrolled leaves. The whole presents to the eye the appearance of a tropical forest in which two persons are sitting on a suspended swing.

Having described my invention, what I claim as new, and desire to secure by Letters Patent, is—

The ornamental design for the back of a toilet-box, mirror or similar article, as herein shown and described.

In testimony whereof I have signed my name to this specification in the presence of two subscribing witnesses.

THEODORE W. FOSTER.
